(No Model.)

L. A. HARPER.
CHURN.

No. 445,272.

Patented Jan. 27, 1891.

FIG. I -

Hitches

Geo. E. Frech

H. J. Riley

By his Attorneys,

Lawrence A. Harper Inventor

C. Snow & Co.

UNITED STATES PATENT OFFICE.

LAWRENCE A. HARPER, OF RUSSELLVILLE, KENTUCKY, ASSIGNOR TO JOHN MILLER, OF SAME PLACE.

CHURN.

SPECIFICATION forming part of Letters Patent No. 445,272, dated January 27, 1891.

Application filed October 7, 1890. Serial No. 367,315. (No model.)

To all whom it may concern:

Be it known that I, LAWRENCE A. HARPER, a citizen of the United States, residing at Russellville, in the county of Logan and State of Kentucky, have invented a new and useful Churn, of which the following is a specification.

My invention relates to an improvement in churns, the construction of which is such as to give to it ease and convenience of operation; and it consists of certain features of novelty to be hereinafter described, and then pointed out in the claims.

In the accompanying drawings, Figure 1 is a perspective view of my improved churn. Fig. 2 is a vertical longitudinal section. Fig. 3 is a vertical transverse section on the line *xx*, Fig. 2.

1 is a suitable base from which extends a pair of standards or uprights 2, braced to the base by braces 4. Journaled in said uprights at about midway of their lengths is the shaft 4^a, from one end of which extends downwardly a pendent rod 5, provided at its lower end with a weight 6, adjustable vertically thereon by means of a set-screw 7, said rod and weight constituting a pendulum. Extending upwardly from the shaft 4, in line with the rod 5, is a crank 8, having a handle 9.

10 is a rocking lever curved upwardly at its center, where it is connected to the rock-shaft 4^a, and curved upwardly at its outer end, where it is bifurcated to provide paired eyes or forks 11.

12 is the oblong churn-body, provided on each side midway of its length with trunnions 13, which are received by the vertical slots 14 at the upper ends of the uprights 2, and on said trunnions between the uprights and the

14^a churn-body are perforated disks or washers 14^a to take up wear. The trunnions act as a lateral support to the churn-body, but do not constitute its perpendicular support.

The perpendicular support of the churn-body consists of a pair of U-shaped stirrups 15, one on each side of the trunnions, the upper ends of said stirrups being pivoted on studs or pins 16 projecting from the sides of the churn-body in line with the trunnions.

15 Intermediate of the lower ends of the pivoted

stirrups are eyes 17, that are received between the eyes 11 of the rocking lever, the stirrups and the rocking lever being pivotally connected by means of cotter-keys or other suitable pivots 18 passing through said eyes at each end of the lever. By means of these stirrups, one at each side of the trunnions, the weight of the churn-body is taken off of the trunnions, whereby the churn-body is balanced away from its axis, its weight being distributed to said stirrups.

The sides 19 of the churn-body are connected by tie-rods 20 outside of the bottom 21 and the ends 22, said bottom and the ends being set in as shown, and similar tie-rods connect the tops of the sides. The top 23 is provided with an opening 24, and the upper portions of the sides are provided with rabbet-grooves 25, upon which rest the removable doors or closures 26, said doors or closures being provided with suitable knobs or handles 27, whereby they may be removed. The inner edges of the top pieces of the top at the ends of its opening are provided with undercut grooves 28, below which and extending from side to side of the body are cleats 29, said grooves receiving the outer edges of the doors. The ends of the doors are strengthened by cleats or braces 30, the doors being formed with lips 31, extending around them excepting at their meeting edges. At one end of the churn is a suitable delivery-spout 32.

It will be seen that a churn in which the body is balanced as above set forth may be easily and conveniently operated. By adjusting the weight 6 upon the pendulum-rod 5 its force may be adjusted to the quantity of cream in the churn.

What I claim is—

1. In a churn, the combination of the standards, the churn-body arranged between the standards and engaging the same, the rock-shaft provided with oppositely-extending arms, and the stirrups connecting the arms and the churn-body and supporting the latter, substantially as described.

2. In a churn, the combination of the standards provided with slots, the churn-body provided with projections or journals engaging the slots, the rock-shaft having oppositely-ex-

tending arms, and the stirrups connecting the arms and the churn-body and supporting the latter, substantially as described.

3. In a churn, the combination of the standards provided with slots, the churn-body arranged between the standards and provided with projections engaging the slots, the rock-shaft having oppositely-extending arms, and the **U**-shaped stirrups centrally pivoted to said arms and having their ends connected to and supporting the churn-body, substantially as described.

4. In a churn, the combination of the standards provided with slots, the churn-body having journals engaging the slots, the rock-shaft having oppositely-projecting arms, the stirrups connecting the arms and the churn-body and supporting the latter, and the pendulum or operating bar secured to one end of the rock-shaft and provided at its upper end with a

handle and provided at its lower end with an adjustable weight, substantially as described.

5. In a churn, the combination of the body provided with trunnions at each side, standards or uprights provided with slots receiving said trunnions, stirrups pivoted at each side of said trunnions, a rock-shaft journaled in said standards, a rocking lever carried by the rock-shaft and pivotally connected with said stirrups, and a pendulum and crank projecting from said shaft, substantially as and for the purpose set forth. 25 30

In testimony that I claim the foregoing as my own I have hereto affixed my signature in presence of two witnesses.

LAWRENCE A. HARPER.
